MAIL COVERING AND MAILING RECORD STRIP

Arthur W. MacKinnon, Shreveport, La.

Application August 4, 1934, Serial No. 738,522

13 Claims. (Cl. 229—70)

This invention relates to a device or devices for obtaining a mailing record upon an enclosure or letter carried within a mail wrapper or covering, and more particularly to a modified form of envelope or mail covering and mailing record strips for use with modified envelopes or mail coverings, by means of which a mailing record may be durably and preferably permanently affixed to the mailed matter or enclosure therein contained.

The general purpose of the invention is to provide for positive and permanent evidence of mailing upon mailed matter, and also to provide an improved mail covering, envelope, or wrapper, and a mailing record strip whereby a mailing identification may be obtained upon the mailed enclosure.

The invention therefore relates to mailing record strips and mail covering constructions which are so devised and formed that the enclosed mailing matter will carry the mailing record, placed upon the message or package during its transmittal, when the enclosure is withdrawn from its envelope or other form of covering.

It is an object of my invention to provide an authentic identification upon mailing matter which passes through the mail in an outer covering or envelope, the identification consisting of the mailing record placed by the post office upon the message or package during its transmittal.

It is a further object of my invention to provide an envelope construction, which will insure and permit the permanent affixing of the mailing record, placed upon the envelope during its transmittal, to the enclosure or letter.

A further object of my invention is the provision of an altered section in the mailing record area of an envelope or mail covering which is adapted to temporarily secure the envelope to its enclosure during transmittal through the mail, and to insure permanent affixing of the mailing record to the enclosure before removal of the enclosure from the envelope.

Another object of my invention is to provide a strip for carrying the mailing record and which is to be used with a mail covering having a cut-out portion in the mailing record area of its mailing face.

A still further object of this invention is to provide a means for determining that the mailing record carried by an enclosure or letter is authentic and was received during the course of its transmittal through the mail.

According to the prior mailing practice where letters, packages and the like are sent through

the mail enclosed in a separate envelope or covering, the postage is affixed to and becomes a permanent part of such covering. The postage is usually placed at the upper right-hand corner of the mailing face carrying the address, in accordance with custom and postal regulations. This postage and the adjacent surface of the mailing face of the covering, which together I broadly term the mailing record area, receive the imprint of the post office cancellation, postmark and the like. After such covering has been freed from its contents there is no positive means of identifying such contents with such mailing record, nor is there any other positive evidence that such contents have been mailed. At considerable expense, governments continue to cause cancellation and postmarking in a manner which serves to deface such postage and record information which has to do with the manner of dispatching, time of day, date, epoch, or place and the like of mailing or receiving of such mailed matter.

Primarily such recorded information is intended for governmental postal purposes as evidence of service, but it is often of value to the addressee or recipient of the mailed matter as evidenced by the preserving of envelopes and the like for the postal mailing record thereon. Such service or record if made positively identifiable with the enclosed mailed subject matter would be most valuable to the public and governmental agencies.

By the means employed comprising my invention I am enabled to produce positive and permanent authoritative identification of matter mailed in coverings not integral with such covering. Such means entails no extra governmental expense or inconvenience.

While my invention is suitable for use in connection with the mailing or its equivalent of all manner of articles enclosed in coverings of paper or the like, I will describe it as applied to the mailing of letters, as the mailed matter, in envelopes as the covering. The invention is herein illustrated as embodied in that form.

The essential characteristic of an envelope constructed according to my invention resides in an altered section in the wall of the envelope positioned to correspond with and of a size and form determined by the mailing record area thereof. The altered section comprises the areas customarily covered by the postage, cancellation, and for the postmark, and is designed so that upon the positioning and affixing of the mailing record upon the message during its transmittal, the mailing record will be permanently fixed to the

contents of the envelope and remain in situ on the contents upon the withdrawal of the latter from the envelope.

This invention also provides a strip for carrying the mailing record and which may receive the latter in whole or in part before or after it is affixed to an envelope having a cutout portion in the mailing record area of its mailing face.

Other detailed objects and advantages of my invention will appear as the description proceeds.

In the accompanying drawing, preferred embodiments of my invention are illustrated.

Figure 1 is a front elevational view of one form of my invention;

Figure 2 is a vertical sectional view on an enlarged scale taken on line II-II of Figure 1;

Figure 3 is a fragmentary elevational view, of an opened envelope of the type shown in Figure 1, with the letter or enclosure freed from the envelope and retaining the mailing record as a part thereof;

Figure 4 is an enlarged plan view of the reverse side of the mailing record strip shown in Figure 1;

Figure 5 is a vertical sectional view taken on line V-V of Figure 4;

Figure 6 is a plan view of a modification of the strip carrying the mailing record;

Figure 7 is a fragmentary plan view of an envelope embodying another modification of this invention;

Figure 8 is a plan view of a mailing record strip embodying a further modification of my invention.

Referring now to the drawing:

An envelope 1 of usual construction is provided with a cut-out portion 2 in the mailing record area of the front of the envelope or its mailing face. The cut-out portion 2 is of substantially the same shape and somewhat larger than the mailing record which comprises the usual postage 3, cancellation 4, and postmark 5.

A strip 6, somewhat larger than the cut-out portion 2, and adapted to carry the mailing record is placed upon the envelope 1 so as to cover the cut-out portion 2. The strip 6 may be of paper or other suitable material and comprises a border 7 and a central section 8 defined by a tearing or perforated line 9. The border or marginal portion of the strip is adapted to be secured to the mailing face of the envelope 1, and in position to cover the cut-out portion 2, by means of an adhesive 10 which is provided in the form of a band spaced outwardly from the tearing line 9 as shown in Figure 5. The central section 8 is adapted to be secured to the letter or enclosure 11 by means of a layer of adhesive 12. The adhesive may also be applied to section 8 and border 7 as one continuous coating.

In practicing this invention, a letter or other matter to be enclosed is placed within an envelope having a cut-out or opening in its mailing face, and the strip 6 is placed over the opening so that adhesive 12 will bind section 8 to the enclosure and adhesive 10 will bind the border 7 of the strip to that part of the envelope's mailing face which surrounds the opening. A stamp 3 is placed in the right-hand end of section 8, and the latter receives, during the passage of the envelope through the mail, cancellation 4 and postmark 5. When the message is received by the addressee, the letter or other enclosure is withdrawn from the envelope, and in so doing, section 8, carried by the letter, is torn from border 7. The letter, therefore, evidences the fact that it has passed

through the mail, and shows also by the postmark the date of its transmittal.

The strip 6 may also be applied to envelope 1 before the insertion of enclosure 11, in which case border 7 is secured to the envelope before the latter receives the enclosure, and section 8 is secured to the enclosure after the latter is placed in the envelope.

The adhesive used may be a water-soluble adhesive or a substantially permanent adhesive, such as, label varnish or other water-insoluble gumming or cement. A substantially permanent adhesive is preferred, as it insures a more permanent union between the strip carrying the mailing record and the letter.

In order to furnish somewhat more conclusive evidence that the mailing record was received by a letter during its transmittal through the mail, the mailing record area of the mail wrapper may be modified so that part of the cancellation and/or postmark ink will reach or be received directly on the letter. The several modifications illustrated in Figures 1 to 7 show constructions which will accomplish this object. For example, the strip 6 (Figs. 1 to 4) may have an opening 13 so located in the central section 8 that part of the ink of the postmark 5 will be received directly on the letter and the rest of the postmark ink together with the cancellation ink will be received by section 8. The provision of opening 13 will thereby prevent improper use of the section 8 after the envelope and letter have been transmitted through the mail. Therefore, any attempt to transfer a section 8 from a letter, which has been through the mail and carries a section 8 and its mailing record, to another letter in order to supply the latter with false evidence of mailing may be readily detected. If the postmark is not completed by an imprint on the letter and within the opening 13, the observer will know that the mailing record is false.

Figure 6 shows a modified form of blank 14 having a rouletted or weakened tearing line 15 and a plurality of perforations 16, which latter are of size and distribution suitable to insure that some part of ink from the postmark and/or cancellation stamp will be impressed on the envelope contents. The function of perforations 16 is the same as that of opening 13 in Figs. 1 to 4, and an observer will know from the continuity of the official postmark and cancellation on the central section of the strip and the letter within the perforations 16 whether the mailing record is true for that particular letter. If the section carrying the mailing record has been transferred and the record, therefore, is false, the official cancellation and postmark imprints will be interrupted and incomplete wherever they cross a perforation, and the parts of the letter left exposed by the perforations 16 will be blank.

In Figure 7, an envelope 17 has an integral separable section 18 bounded by a tearing line 19 similar to tearing line 15 shown in Figure 6. Section 18 may be secured to an enclosed letter in the same manner as section 8 in Figures 1 to 3 and is adapted to receive the mailing record. Section 18 is also provided with perforations 20 similar in size and arrangement to the perforations 16 of Fig. 6. These perforations 20 are intended to serve the same function as the opening 13 in Figs. 1 to 4 and the apertures 16 of Fig. 6.

Figure 8 shows a tape 21 constituting a plurality of strips 22, separated by a perforated or weakened line 23. Each strip 22 is divided into a

central section 24 and border 25 by means of a tearing line 26. The tape 21 is intended for use with a franking machine, and whenever mailing matter is to be posted, the machine may be operated to print the mailing record on one of the strips 22, and the latter torn from the tape and applied to the mail covering or envelope and its enclosure or letter in the manner described in connection with the modification shown in Figs.

10 1 and 2.

It is clear that the structure of my mailing record strip may be adopted by the postal department of any government as a stamp form. In such a case, the postage stamp, or other indicia of value, may be engraved, or otherwise imprinted, directly upon the strip and preferably in the relative position of the postage 3 as shown in the drawing.

15 It will be understood that the strips 6 and 14 shown in Figs. 1 to 6 may receive the mailing record in whole or in part before they are applied to an envelope in accordance with this invention. In this case, the strips need not be provided with ink transmitting perforations.

20 25 The central section of the strips 6, 14 and 22 is preferably of substantially the same size and shape as the mailing record and the cut-out portion. The tearing line may register with the edge of cut-out portion 2 or may lie inside thereof. 30 It is preferred that a portion 27 of the border be left bare of adhesive, in order to minimize the possibility of the border becoming attached to the enclosure or letter.

35 For the purpose of this specification and the claims to follow, the term "mailing record" is intended to include the postage and the impression of cancellation, postmark, and any other marking of mailing, collectively or in any combination less than the whole, which it may be desired to preserve or cause to be preserved to give the identifiable evidence of mailing desired, including any permissible private marking.

40 Having thus described the form of altered section of my improved envelope, it will be understood that the method of use of coverings and mailing record strips constructed in accordance with this invention will be apparent to the user. It will also be apparent to the recipient when a tearing line is an element of the mail covering, 45 that tearing is required at the tearing line.

50 My invention has many important special uses and is suitable and desirable for general use in mailing and the like. The invention may be used to advantage in the mailing of documents, legal and otherwise, of military orders, of patent office records and various other governmental mailings and communications. The desirability for general use will become apparent with the general recognition of the real value of such affixed mailing record.

55 From the above description of my improved envelope it is clear that novel means are provided, whereby mailed matter not integral with its covering may be positively and permanently identified with authoritative evidence of such mailing.

60 It is to be understood that various changes in arrangements may be resorted to and that I consider all variations which may be made under the teaching of this invention to fall within the scope 65 of the appended claims.

70 This application is a continuation in part of my copending application Serial No. 607,384 filed April 25, 1932.

75 What I claim is:

1. In a mail covering for obtaining a mailing

record upon its enclosure, an envelope having a cut-out portion in the mailing record area of its mailing face, said cut-out portion being of substantially the same shape and size as the mailing record, and a strip adapted to receive the mailing record and to overlie said cut-out portion, said strip being provided with adhesive on its under side for securing the marginal part of the strip to said mailing face and the central part of the strip to the enclosure through said cut-out portion. 10

2. In a mail covering for obtaining a mailing record upon its enclosure, an envelope having a cut-out portion in the mailing record area of its mailing face and a strip adapted to overlie said cut-out portion, said strip having a border, a tearing line defining the inner edge of the border, and adhesive on its under side for securing the border to said mailing face and the central part of the strip to the enclosure through said cut-out portion. 15

3. In a mail covering for obtaining a mailing record upon its enclosure, an envelope having a cut-out portion in the mailing record area of its mailing face, said cut-out portion being of substantially the size and shape of the mailing record, and a strip adapted to overlie said cut-out portion, said strip having a border, a central part of substantially the size and shape of the mailing record, a tearing line between said border and said central part, and adhesive on its under side for securing said border to said mailing face and said central part to the enclosure through said cut-out portion. 25

4. A mailing record strip for use with a mail covering having a cut-out portion in the mailing record area of its mailing face, comprising a central section for bearing the mailing record, a border separable from said central section, and an adhesive coating on the under side of both said border and said central section. 35

5. A mailing record strip comprising a central section bearing the postmark and stamp of a mailing record, and a border separable from and surrounding said central section. 45

6. A mailing record strip for use with a mail covering having a cut-out portion in the mailing record area of its mailing face, comprising a central section for receiving the mailing record, a tearing line defining the boundary of said central section, a border, and an adhesive coating on the under side of both said border and said central section. 50

7. A mailing record strip for use with a mail covering having a cut-out portion in the mailing record area of its mailing face, comprising a central section for receiving the mailing record and being of substantially the size and shape of the said record, a border surrounding said central section, a weakened tearing line constituting the dividing line between said central section and said border, and an adhesive coating on the under side of both said border and said central section, the adhesive on said border being spaced outwardly from said tearing line. 55

8. A mailing record strip for use with a mail covering having a cut-out portion in the mailing record area of its mailing face, comprising a plurality of separable units, each of said units comprising a central section for receiving the mailing record, a border surrounding said central section, a tearing line constituting the dividing line between said central section and border, and an adhesive coating on the under side of both said border and central section. 70

50

55

60

65

70

75

9. A mailing record strip comprising a central section adapted to carry a mailing record, and a border separable from and surrounding said central section, said central section having at least one perforation in the postmark and cancellation area.
10. In a mail covering for obtaining a mailing record upon its enclosure, an altered portion for carrying the postmark, cancellation and stamp constituting the mailing record, said portion having a tearing line defining a boundary for the mailing record area, an adhesive backing for that part of the covering within the confines of said tearing line for securing the same to the enclosure, and at least one perforation or opening in the mail covering, within the tearing line, and in such position that a part of the mailing record will be impressed upon the enclosure.
11. In a mail covering for obtaining a mailing record upon its enclosure, an envelope having a cut-out portion in the mailing record area of its mailing face, a strip somewhat larger than said cut-out portion for carrying the cancellation and the stamp constituting the mailing record, and an adhesive coating on the under side of said strip for securing the outer part of the
- strip to said mailing face and the central part of the strip to the enclosure through said cut-out portion, said central part of the strip having at least one perforation or opening in such position that a part of the mailing record will be impressed upon the enclosure.
12. In a covering for obtaining a mailing record upon its enclosure, a separable portion formed integral with the covering and located for reception of the mailing record, said portion being defined by a tearing line, having an adhesive on its under side for securing the same to the enclosure, and having at least one perforation in such position that a part of the mailing record will be impressed directly upon the enclosure.
13. In a mail covering for obtaining a mailing record upon its enclosure, an altered portion for carrying the cancellation and stamp constituting the mailing record, said portion having a tearing line defining a boundary for the mailing record area, and a substantially permanent adhesive coating on the under side of that part of the covering within the confines of said tearing line for securing the same to the enclosure.

ARTHUR W. MACKINNON.
